Application January 23, 1935, Serial No. 2,998

6 Claims. (Cl. 110—21)

This invention relates to an apparatus, and method for superheating steam into a dry blast, and burning stumps thereby.

Plans have been described for burning and destroying stumps and roots, by the application of wood fuel, and oil fuel, thereto, and the digging of pits and depositing such fuel and burning the same in contact with stump roots under covers, and even adding steam to the flames. Such plans have not been successful for many reasons, including the great amount of labor and material necessary for such burning, which requires many days for accomplishment of only a little burning. Lack of circulation of air to the fire retards the burning, and continued contact of oil flames tends to deposit a coating of carbon for delaying the fire. Under a cover there is constantly formed a thick scale of deadening charcoal on the surface to be burned. Any mere addition of moist steam into the flaming fuel is a dampener and will not cause any greater penetration of the heat into the wood to be burned, and all apparatus so far designed has been impracticable for burning stumps in their natural locations.

After repeated experiments with the burning of huge stumps and roots thereof, in clearing western land, I have discovered and invented both a practicable and successful apparatus and method for burning and destroying stumps and roots thereof, at low cost and very rapidly, and solely by projection against an ignited surface of such wood to be burned, of hot dry superheated steam. Said steam so heated by a simple and inexpensive apparatus, and said apparatus, in turn, heated by the stumps and roots being burned.

I have found that by heating water into steam and superheating the same to a high degree, in a tube, under approximately 40 pounds pressure to the square inch, and passing such superheated steam slowly through the tube and releasing the same through a small nozzle, that such superheated steam will then be projected from such outlet at a high velocity in line of the nozzle outlet, for a considerable distance.

Such projected heated steam will carry and draw along a proper supply of air for oxygen necessary for rapid consumption of the wood, and the drying out sap when containing any pitch or resinous qualities, will not impede such burning and eating away of the dried out wood surface. When the stream of superheated steam, and atmospheric air entrained therewith, is directed against an ignited surface of a stump, it provides a fanning blast, which soon raises such ignited surface to a white heat. This produces an

incandescent charcoal surface which continues to extend backward and in advance of the blast with comparatively rapid rate of combustion, and practically smokeless.

It is therefore an object of this invention to first provide a suitable light portable apparatus for generating and superheating steam, for the process of burning and destroying stumps and roots by the projection of such hot blast against the surface to be burned. 10

Another object is to provide such an apparatus, suitable to withstand the high degree of heat to which it must be subjected in successfully conducting such process. Such apparatus to be preferably constructed of wrought iron tubing, and bent into coils or convolutions upon itself, for providing a large heating surface in a relatively small space for easy heating, and for close application thereof to the surface to be burned. 15

A further object is to provide means for slowly feeding a small supply of water into one end of the tube, with a small nozzle in the other end thereof, for the projection of superheated steam therefrom.

A still further object is to provide a method for destroying stumps and roots, solely by forming and projecting superheated steam against the ignited surface thereof, and heating the steam by the burning stump. 25

With these, and other objects as may herein- 30 after appear, I have illustrated a suitable apparatus by the accompanying drawing, of which:

Figure 1 represents a side elevation of the apparatus, with parts broken away,

Figure 2 represents an elevation of the front 35 end thereof.

Like numerals on the different figures represent like parts.

Numerals 1, 1, represent a pair of spaced skids or runners upon which heating coils are supported, moved and transported. The skids are attached together by side bars 2, 2, which extend upward along the heating tube coils 3—to—6, and connected by rivets 2', for retaining said coils in suitable adjustment, under all conditions. 40 45

The heating tube is preferably formed of wrought iron, and welded from several sections into one continuous tube, bent upon itself for facility in heating and operation. For lessening the height that would otherwise be required, the 50 section 5 may be carried down beneath the others and again up to 7, and uniformly terminates in a small jet or nozzle 8.

For convenience in illustrating the operations, I have indicated a stump A, with a cavity being 55

burned as B. The forward end of the coils is maintained in close proximity to the object to be burned. Thus heat from the burning object always aids in the heating of the tubes, and is generally sufficient therefor, while the burning of the object is facilitated by the blast created by the heated tubes. The nozzle 8 is preferably located at a distance of approximately one to two feet from the surface to be burned, to permit the spread of superheated steam from the nozzle to cover a proper area for burning.

Within the tube 3 may be mounted a smaller tube 9, provided with a series of outlet perforations 10. A bolster 11, supports the rear end of the smaller tube, and the front end may be supported by a similar bolster or merely by folds of wire 12. This wire is preferably packed loosely in the tube and continued throughout the coils of the tubing, for the purpose of transmitting heat from the walls of the tubes to the interiors, and for breaking up particles of steam or moisture, and also for impeding the free flow of the steam to insure that a high degree of heat be imparted thereto. The loosely packed wires are preferably positioned in the tubing before the bending thereof, for ease in inserting the same, and in bending of the tubes. The wires being so packed loosely, leave sufficient passageways for the steam while serving the other purposes mentioned.

13 indicates a welded connection between tubes 3 and 4, while 15 indicates a threaded connection at the opposite end of 3, with a hollow handle 14. This handle is formed with sufficient length to permit the operators to easily manipulate the heater and without personal injury from the heat. Within said handle may be positioned a water supply pipe 16, for conducting a small supply of water to the perforated tube 9, into which the front end of the pipe is placed. Any suitable packing may be wrapped around the pipe at 17, to prevent steam and heat from backing into the handle 14. A small nipple 18 is affixed in the rear end of the pipe, and with valve 19, and supply hose 20 and pipe 21, provides a supply of water from a suitable pressure source.

Such source may be a light portable pressure tank 23, with the pipe 21 mounted therein, and a filler cap 22 for placing a supply of water therein. Any suitable pressure is exerted through tube 24, and connecting nipple 24', and is supplied by any simple hand pump as 25. A gage 26 indicates the amount of pressure which is preferably near 40 pounds per square inch, for forcing the water into the heating tubes, and against any back pressure from the steam formed. Any simple safety valve, not shown, may be attached to the plug 26. It is unnecessary to operate the pump, except at short periods, between intervals of several hours, as little water is necessary for the required steam.

In order to provide rigidity between the handle and the heating tubes and skids, a connecting brace 27 may be attached at one end, to one of the holding rivets 2' and the other end by a clamp 27'.

In operation, the bark is preferably removed from the portion of the stump or root to be burned, and the front portion of the coils then placed adjacent to the object to be burned, with the nozzle 8 spaced back in line with the barked portion. Any desired flame is then applied to the outside of the coils and to the adjacent stump and a small amount of water supplied into the tube 9. Such water is speedily converted into

steam, which then passing along through the heated tubes and interior wires is thereby superheated to a high degree and escapes from such 40-pound pressure out through such small nozzle and proceeds with great velocity therefrom against such barked surface of the stump or root. In a brief period of time such superheated steam absorbs the moisture from, and dries such wood surface and forces such flame against and into the surface of the stump to burn the same. As 10 the outside of such wood is burned away, the front end of the tubes may be lowered by elevating the handle 14, whereby the line of projected superheated steam will burn downward and provide a cavity into which the front portion of the coils may be later pressed, and there heated by the adjoining burning area. The handle is then lowered, and the lines of dry steam directed against a new exposure beyond the first portion burned away. By repeating the operations, a section of the stump or a root in front of the apparatus is speedily burned away. Roots are similarly destroyed by first removing the earth and bark from top sides thereof, and then depressing the front of the tubes, till the nozzle is 25 in line with the portion to be burned and the dry steam then projected against the ignited surface to be burned. The roots may also be followed when the stump is burned.

In order to properly first heat the tube coils, 30 only a small amount of wood or other suitable fuel is required. Ordinarily there is a sufficient amount of wood in the immediate vicinity of the stumps, to provide all the heat required. Such wood fuel is not necessarily shown, but is preferably burned beside the coils, and the flames from the burning thereof, envelop the coils, and heat the same to the desired degree and ignite the surface to be burned. The same supply of wood, if piled alongside the stump and burned, 40 would at most but char the outside of the stump, as the heat and flames from the fuel would not penetrate the stump, but rise up and escape along and above the same. When the stump adjacent the apparatus is burning, then little or no 45 additional fuel is required.

The steam will be raised to a sufficient pressure for entraining or aspirating atmospheric air against the stump before the tubes reach a red heat, but for best results it is advisable to heat 50 a portion of the tubes to a dull red color. When such tubes are so heated the dry superheated steam will be expelled from the small nozzle with great velocity, and invisible to the naked eye.

The pressure of the heating tubes or coils is 55 automatically maintained substantially the same as in the water tank. The necessary supply of water to the lower tube is held back if the pressure in the coils exceeds that in the tank, and as soon as the pressure of steam in the tubes falls below 60 that in the tank, then the water again flows into the lower coils, for producing more steam and vapor till the pressure is again equalized.

Where insufficient wood fuel is available for heating the coils, I have provided an alternate 65 means for supplying such first heat and flame by spraying burning oil upon such tubes and coils. Such alternative means is shown in Figure 1 of the drawing.

28 represents a portable oil tank, provided with 70 a removable pipe cap 29 for filling the tank with fuel oil. The oil is discharged from the tank through pipe 30, and hose 31, and valve 31'. A feed pipe 32 is attached along the handle by clamps 32', and provided with a regulator and 75

cut-off valve 33 for convenient use by the operator.

A nipple 34 connects the outer end of the pipe 32, with a pair of nozzles 35 and 36, and these nozzles are supported on a short pipe 37, which is threaded into one of the heating coils. Said nozzles are positioned for discharging sprays of fuel oil over the coils. A valve 38 is provided in the pipe 37 for permitting a small supply of steam to flow from the coils and mingle with the oil for expanding, and forcing the same to flow from such nozzles in suitable sprays for burning over said coils, for heating the same and forming a supply of vapor thereby.

15 A pressure gage 39 is mounted in the top of the oil tank 28, and a suitable air pressure supplied over the oil, through a nipple 41, to which may be attached an air hose and pump similar to those shown as 24 and 25 for the water tank. Any 20 suitable safety valve may be attached to the plug 40.

In order to provide priming steam for first mingling with the fuel oil behind the nozzles 35 and 36, the heating coils 3 to 7 are slightly heated. 25 This may be easily accomplished by a small amount of the fuel oil or kerosene, placed beneath the coils in a pan or on any suitable agent, and ignited. Sufficient steam is quickly generated thereby, for forcing a supply of such steam behind, and out through such nozzles, with oil spray for heating the coils thereby.

Only a small supply of fuel oil is required for maintaining the coils or tubes at a sufficient temperature for forming the necessary superheated 30 steam for burning stumps. The same amount of oil, if sprayed directly upon the stump and there burned, would produce no material destruction of the stump, as the flames therefrom would rise up along the sides of the stump, and leave a sooty 40 carbon deposit upon the same.

Where sufficient wood fuel can be cheaply obtained for heating the coils, then the means for heating by oil is disconnected. This is easily 45 done, by removing the oil feed hose 31, from a nipple 41 and feed pipe 32, and closing the steam valve 38.

While I have illustrated an apparatus with elongated coils of tube constructed on supporting 50 members, yet such forms are optional, and I have found that a $\frac{3}{4}$ inch wrought iron pipe formed either into long or circular coils may be utilized without support skids and may be easily carried by one man into areas inaccessible for vehicles.

In general the apparatus and method are used 55 for severing large stumps at the ground surface without consuming the upper portion of the stump, and also are used for following up and burning out the larger roots from below said surface.

60 Having described my invention, I claim as new:

1. Apparatus for burning stumps and the like, means for generating superheated steam, means for igniting a portion of the stump to be burned and for initially heating said steam generating means, means for directing a blast of superheated steam onto the ignited portion of the stump and

to aspirate air therewith to cause combustion of the stump, the steam generating means being so constructed that it may be positioned adjacent the burning portion of the stump so that the heat of said burning portion will serve as a source of 5 heat for said generating means.

2. Apparatus for burning stumps and roots in their natural locations, comprising a device for generating and superheating steam, said device including means for flashing water into steam 10 and means forming a tortuous passage wherein steam is superheated, and means for projecting such superheated steam against an ignited area of an object to be burned whereby atmospheric air is entrained there-against for increasing and 15 continuing the burning of such object, said generating and superheating device being portable for positioning thereof adjacent the burning area of such object whereby the heat created by the burning object may be utilized as a source of 20 heat for generating and superheating steam in said device.

3. Apparatus for burning stumps and roots thereof in their natural setting, comprising means for generating steam from water, means for supplying the necessary water for such steam, means for superheating such steam to provide a dry blast thereof and for projecting such dry blast against the object to be burned, such apparatus being portable for positioning adjacent the burning 30 surface of such object to be burned so that the heat from such burning object is utilized for the continued heating of such apparatus and the superheating of steam generated therein.

4. A method of burning stumps and the like, 35 comprising igniting a portion of the stump, initially generating superheated steam, directing a blast of the superheated steam together with aspirated air onto the ignited portion of the stump, and utilizing the heat of the burning stump for 40 the continued generation of superheated steam to be directed there-against without the use of additional fuel.

5. A method of burning stumps, comprising the building of a flame adjacent the stump and igniting a portion of such stump and generating superheated steam to form a dry blast by such flame, projecting such dry blast of superheated steam against such ignited portion of such stump for enhancing the combustion thereof and the 50 continuation and increasing of the combustion of such stump by the forcing of the fire into the wood thereof by said blast, and the continued generation of such superheated steam blast by utilizing the heat created by said burning stump. 55

6. A method of burning stumps, comprising igniting a surface of a stump to be burned, producing a highly heated steam, directing a blast of such steam onto the ignited surface of a stump whereby air is entrained by said blast against the burning surface of the stump to support combustion thereof, and utilizing the heat of the burning stump as a source of heat for continuing the production of highly heated steam to be used in 60 said blast.

JACOB JONES.
